UNITED STATES PATENT OFFICE.

WASHINGTON I. WOLVERTON, OF ANDERSON, INDIANA, ASSIGNOR TO THE BUCKEYE MANUFACTURING COMPANY, OF SAME PLACE.

DESIGN FOR A WHIFFLETREE-CLIP MEMBER.

SPECIFICATION forming part of Design No. 34,930, dated August 13, 1901.

Application filed July 3, 1901. Serial No. 67,041. Term of patent 14 years.

To all whom it may concern:

Be it known that I, WASHINGTON I. WOLVERTON, a citizen of the United States of America, residing at Anderson, in the county of Madison and State of Indiana, have invented and produced a certain new and useful Design for a Whiffletree-Clip Member, of which the following is a specification, reference being had to the accompanying drawings, in which—

This design consists of a substantially circular plate 1, having an integral segmental flange 2 projecting radially from its edge, the upper faces of the plate and the flange being flush with each other and the outer curved edge of the flange being rounded off at its upper corner, as at 3, and the flange itself being about half the thickness of the plate. Formed centrally through the plate is a hole 4, and around the hole, on the upper side of the plate, is formed a circular flange 5. 25 Depending from the edge of the plate just under the segmental flange is a depending slightly-curved bar 6, which is provided at its lower end with a right-angled arm 7, which is provided with a hole 8 near its end coincident with hole 4.

I claim as my design—

The design for whiffletree-clip member substantially as herein shown and described.

In testimony whereof I hereunto affix my 35 signature, in the presence of two witnesses, this 28th day of June, 1901.

WASHINGTON I. WOLVERTON.
